CLAIM

The ornamental design for a fenestration assembly, as shown and described.

DESCRIPTION

FIG. 1 is a first perspective view of the fenestration assembly, showing the new design.

FIG. 2 is a second perspective view of the fenestration assembly of FIG. 1.

FIG. 3 is a front view of the fenestration assembly of FIG. 1.

FIG. 4 is a back view of the fenestration assembly of FIG. 1.

FIG. 5 is a first side view of the fenestration assembly of FIG. 1.

FIG. 6 is a second side view of the fenestration assembly of FIG. 1.

FIG. 7 is a top view of the fenestration assembly of FIG. 1; and,

FIG. 8 is a bottom view of the fenestration assembly of FIG. 1.

The broken lines in the drawings depict portions of the fenestration assembly that form no part of the claimed design.

1 Claim, 5 Drawing Sheets
